(57) **CLAIM**

The ornamental design for a case for electronic device, as shown and described.

DESCRIPTION

The file of this patent contains at least one drawing/photograph executed in color. Copies of this patent with color drawings will be provided by the office upon request and payment of the necessary fee.

FIG. 1 is a front perspective view of a first embodiment of a case for electronic device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view thereof, showing encircled portion "9" of FIG. 6;

FIG. 10 is a front perspective view of a second embodiment of the case for electronic device showing my new design;

FIG. 11 is a rear perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof; and,

FIG. 17 is a bottom plan view thereof.

The dash-dash broken lines throughout the drawing figures depict portions of the case for electronic device that form no part of the claimed design. The dash-dot-dash broken lines in FIGS. 6 and 9 are included to show an enlarged view only and form no part of the claimed design.

1 Claim, 17 Drawing Sheets
